ABSTRACT

A planishing machine and process for reshaping parts wherein an anvil roll supports a brake shoe plate with a surface of the desired shape of plate. The anvil roll has a radial slot to receive the brake shoe web. Paired form rolls for ironing the plate against the anvil roll under force are swung on paired arms to advance and retract each form roll relative to the anvil roll. The form rolls are triangulated relative to each other and to the anvil roll and to avoid interference in the confined workpiece space and to provide separate control and power means to advance and retract each form roll. Coordinated drives turn the anvil roll and the form rolls at about the same peripheral surface speed.

FIG.3

PATENTED JUL 18 1972

3,677,053

SHEET 4 OF 4

PLANISHING MACHINE

This invention relates to a planishing machine which corrects the contour inaccuracies of a part resulting from the imposed heat and force applied to the part in welding the part from component pieces.

A vehicle brake shoe is such a part and includes an arcuate plate and an arcuate web welded together. The heat and force of the welding operation deforms the plate and web and produces high and low spots at the welds requiring correction to within acceptable manufacturing tolerances.

With the foregoing in view, it is a primary object of the invention to provide a planishing machine for correcting welded brake shoes, for example, which is simple in design and construction, inexpensive to manufacture, and easy, reliable, efficient, and inexpensive to use.

An object of the invention is to provide a planishing machine which is easily modified to operate on different size brake shoes as by changing the anvil roll and/or the form rolls.

An object of the invention is to provide a machine which is capable of planishing several sizes of brake shoes on a single anvil roll such as for example, shoes of 14 to 18 inch diameter on an anvil roll of 14 inch diameter.

An object of the invention is to provide a machine which will planish brake shoes of various widths on a single anvil roll within the diametrical range of the anvil roll.

An object of the invention is to provide a machine which eliminates the need for a die for each size brake shoe and a huge press to supply the needed force, such as a 400 ton press.

An object of the invention is to provide an anvil roll of desired size and shape and two form rolls forceably engagable with the anvil roll to planish the brake shoe therebetween.

An object of the invention is to triangulate the anvil and form rolls and their operating mechanism so that both form rolls can be brought to bear on the brake shoe in the confined work space so that both form rolls engage the brake shoe at the same time over a long travel distance.

An object of the invention is to drive the anvil and form rolls at substantially the same peripheral surface speed to minimize stresses imposed on the welds of the brake shoe.

An object of the invention is to provide a relatively small planishing machine, as compared to a 400 ton press, which is capable of exerting a line force on the workpiece up to 800 tons per square inch to shape the workpiece by applying up to 25 tons of force from each of the cylinders to force the form rolls against the workpiece with line contact therebetween.

An object of the invention is to roll-form or planish the workpieces to eliminate the operation of scoring or cross-hatching the surface of the workpiece to break skin resistance and reduce spring back as is the usual practice in reshaping a workpiece in a press.

An object of the invention is to provide a machine which applies a rolling force on a line to the workpiece to overcome skin resistance and spring back.

An object of the invention is to provide a machine which can be integrated easily with other machines which cannot be done with a large press requiring special below-floor foundations, and which is easily automatically loaded, unloaded, and/or included in an automated transfer machine.

An object of the invention is to provide a machine which can only receive a single workpiece at each workpiece position on the anvil roll so that double loading or hitting is eliminated.

An object of the invention is to provide an anvil roll which is capable of receiving a plurality of workpieces so that they may be loaded, rolled, and unloaded at various circumferential positions on the anvil roll in a continuous operation which may be easily automated.

An object of the invention is to provide a process for straightening parts which alters the character of the workpiece by changing it from a malformed part to a correctly formed part, by superposing the part on an anvil roll base, engaging the part with form rolls under pressure, and rotating the anvil roll and the form rolls to pass the part therebetween to subject the part to line-force radially between the anvil and form rolls

with the line force moving the material and overcoming skin and sub-strata resistance to eliminate spring-back in any substantial degree to thereby reshape the part.

These and other objects of the invention will become apparent by reference to the following description of a planishing machine embodying the invention taken in connection with the accompanying drawings in which:

FIG. 1 is an end elevational view of the planishing machine of the invention, partly in cross-section, with parts broken away and in dotted lines to show interior construction.

FIG. 2 is a cross-sectional view of the machine shown in FIG. 1, taken on the line 2—2, thereof showing a brake shoe in cross section between the anvil roll and a form roll.

FIG. 3 is a cross-sectional view of the machine shown in FIG. 1 taken on the line 3—3 thereof showing the anvil roll drive means.

FIG. 4 is a cross-sectional view of the machine shown in FIG. 1 taken on the line 4—4 thereof showing the form roll support and drive means.

FIG. 5 is a side elevational view of a brake shoe, showing the welds in dotted lines.

FIG. 6 is a cross-sectional view of the brake shoe shown in FIG. 5 taken on the line 6—6 thereof.

FIG. 7 is a top plan view of the brake shoe shown in FIG. 5 as seen in the direction of the arrow 7; and

FIG. 8 is a partial end elevational view of the connections between the swing arms and the rams taken in the direction of the arrow 8 of FIG. 1.

Referring now to the drawings wherein like numerals refer to like and corresponding parts throughout the several views, the planishing machine and brake shoe shown therein to illustrate the invention comprises a frame 20. An anvil roll 21 is rotatably supported on the frame 20 and has a surface 22 and a radial slot 23, FIGS. 1 and 2. The brake shoe 24, FIGS. 5-7, has an arcuate plate 25, an arcuate web 26, an inter-connecting welds 27, and a key-tab 28 on web 26 lying in an aperture of the plate 25. The tab 28 and plate 25 are also welded together. The anvil roll slot 23 receives the brake shoe web 26

and the anvil roll surface 22 lies behind the brake shoe plate 25, FIG. 2. A space 29 exists between the web 26 and the bottom of the slot 23. A pair of form rolls 30 and 31 engage the brake shoe plate 25. Paired swing arms 32 and 33 rotatably support the form roll 31. Paired swing arms 34 and 35 rotatably support the form roll 30. A ram 40 and a power cylinder 41 are connected to the swing arms 34 and 35 to advance and retract the form roll 30. A ram 42 and power cylinder 43 are connected to swing arms 32 and 33 to advance and retract the form roll 31. Drive means, later described, turn the anvil roll 21 and form rolls 30 and 31 at substantially the same peripheral surface speed to planish the brake shoe plate 25, web 26, and connecting welds by rolling the brake shoe 24 between the rolls. As the web 26 is free to move into the space 29, the reforming of the plate 25 corrects the web 26 but without encountering resistance from the web 26.

More particularly, an axle 50 supports the anvil roll 21. The anvil roll 21 is keyed or splined on the axle 50. Sleeves 52 and 53 and bearings 54 and 55 rotatably support the axle 50. The axle 50 and sleeve 52 are keyed or splined to each other for rotational drive from the sleeve 52 to the axle 50. The axle 50 is thus mounted for angular movement with the sleeves 52 and 53 and for axial movement relative to the sleeves 52 and 53.

A worm gear 56 is keyed on the sleeve 52. An outboard bearing 57 supports the sleeve 52 outwardly of the worm gear 56, FIG. 2. A worm 58 drives the worm gear 56. A shaft 59 drives the worm 58, which, in turn, is driven by a pulley 60, belt 61, pulley 62 and motor 63. It is apparent that by energizing the motor 63, that the anvil roll 21 is driven with reduced speed and increased force.

A power cylinder 64 is fixed on the frame 20 axially of the axle 50. A piston rod 65 extends from the cylinder 64 and is connected to the axle 50. A free wheeling connector 66 allows the axle 50 to move angularly without rotating the piston rod

75 65.

To replace the anvil roll 21, the power cylinder 64 is actuated to withdraw the piston rod 65 which pulls the axle 50 out of the anvil roll 21. With the axle 50 pulled from the anvil roll 21, it may be replaced with a like or different roll 21 and remounted by operating the cylinder 64 to extend the piston rod 65 which moves the axle 50 axially through the anvil roll 21 and into the sleeve 53.

Referring now to the form roll supports and drives, uprights 70 and 71 are part of the frame 20. A pivot pin 72 is supported between the uprights 70 and 71, FIG. 4. The swing arms 32 and 33 are bearinged on the pivot pin 72 so that the arms may swing thereon. A sprocket gear 73 is sleeved on the pin 72. A spur gear 74 is sleeved on the pin 72. The sprocket gear 73 and spur gear 74 are keyed together by a stud 75. A pinion gear 76 engages the spur gear 74. A stub shaft 77 is rotatably bearinged on the frame 20. The stub shaft 77 is keyed to the pinion gear 76. A sprocket gear 78 is keyed to the stub shaft 77. The swing arms 32 and 33 may be viewed as triangular and that the pin 72 pivotally mounts the arms 32 and 33 at the pivot corner.

At a second corner of the swing arms 32 and 33, an axle 80 is pivotally bearinged between the swing arms 32 and 33 and supports the form roll 31 to which it is keyed. An outboard sprocket gear 81 is also keyed on the axle 80. An endless chain 82 connects drive from the sprocket gear 73 to the sprocket gear 81, axle 80 and form roll 31.

A cross-bar 83 spans the swing arms 32 and 33 at their third corner, FIGS. 1 and 8. Clevises 84 and 85 are welded on the cross-bar 83. A connecting rod 86 lies between the clevises 84 and 85. A wrist pin 87 pivotally mounts the connecting rod 86 relative to the clevises 84 and 85. A socket 88 is formed in the top end of the connecting rod 86. The ram 42 of the power cylinder 43 fits in the socket 88. Outward movement of the ram 42 pivots the swing arms 32 and 33 on the pivot pin 72 to move the form roll 31 on the swing arms 32 and 33 toward the anvil roll 21. A drag link 89 bolted between the ram 42 and connecting rod 86 moves the form roll 31 away from the anvil roll 21 with inward movement of the ram 42. The power cylinder 43 has trunnions 96 which are bearinged in trunnion sockets 97 on the frame 20.

The swing arms 34 and 35, form roll 30, cylinder 41, and ram 40 are similarly equipped and integrated as described in connection with the swing arms 32 and 33. An idler sprocket gear 93 is mounted on the frame 20.

A fluid motor 90 is mounted on the frame 20. A pinion gear 83 is driven by the fluid motor 90. A large spur gear 83 A is driven by the pinion gear 83. A prime sprocket gear 91 is driven by the spur gear 83 A via a shaft 83 B. An endless prime chain 92 leads over and around prime sprocket gear 91 and the sprocket gear 78 at arms 32 and 33, and the sprocket gear 78 at arms 34-35. The prime chain 92 leads under the idler sprocket gear 93.

The fluid motor 90 thus drives the prime chain 92 which in turn drives the sprocket gears 78. The sprocket gears 78 drive the stub shafts 77 and pinions 76. The pinions 76 drive the spur gears 74 and attached sprocket gears 73. The sprocket gears 73 drive the chains 82. The chains 82 drive the sprocket gear 89 on the form roll axle 80 at each form roll 30 and 31.

The fluid motor 90 speed and reduction to the form rolls 30 and 31 and their circumference is coordinated with the motor 63 speed and reduction to the anvil roll 21 and its circumference to turn the rolls 21, 30 and 31 at substantially the same peripheral surface speed to avoid skidding and imposing cross-strain on the welds of the brake shoe 24. The fluid motor 90 has been found advantageous as it provides a resilient drive which allows the form rolls to increase or decrease in speed at the anvil roll without undue load in either drive train.

The forces exerted on the brake shoe 24 may be varied by adjusting the fluid pressure supply to the power cylinders 41 and 43 and coordinated to the size of the form rolls 30 and 31 for exerting the desired rolling line force on the brake shoe 24. The speed of the rolls may also be coordinated to the exerted forces imposed on the brake shoe.

The brake shoe 24 is placed on the anvil roll 21 with the web 26 in the slot 23. Spring detents, adjustable studs, magnets, etc. may be used to hold the brake shoe 24 on the anvil roll 21 as it approaches, passes, and leaves the form rolls 30 and 31.

The form rolls 30 and 31 may operate in continuous forced engagement or may be alternately advanced and retracted by suitable servo-mechanisms as suits the needs and desires of the particular operation.

In operation, the planishing machine is hand loaded or preferably automatically loaded and unloaded. In a brake shoe operation, the machine may be located after the welding machine and ahead of down-stream operations. Thus the shoes are straightened immediately and may be used immediately.

In processing parts in the planishing machine, one form roll 30 and 31 makes first contact under low applied force with the leading edge of the workpiece as it is advanced angularly by the anvil roll 21. Upon engagement with the form roll the applied force is increased. The second form roll 30 or 31 then makes contact under low applied force with the leading edge of the workpiece; the force applied to both form rolls 30 and 31 then is increased to the desired maximum. Thus the workpiece is planished from end to end with the desired maximum force with the form rolls applying the force along line of contact of the periphery of each form roll. While this contact is described as "line contact" it will be understood that the maximum line of force will be at the apex of the form roll periphery relative to the workpiece with areas of increasing and decreasing applied force on either side thereof. The engagement forces are increased and decreased by controlling the pressures supplied to the cylinders 41 and 43 by conventional means and the indexing controlled by means such as cams coordinated to the length of the workpiece or stops turning with the anvil roll. The speed of rotation is also coordinated to the applied force and the size of the workpiece.

The planishing machine is thus capable of planishing large brake shoes for the biggest trucks and small brake shoes for the littlest cars as the machine is variable as needed to apply the desired force at the desired rotational speed as best suits the workpiece being planished.

While a brake shoe has been described as a suitable workpiece, it will be understood that this is exemplary and that other parts may be shaped by the machine as the scope of the invention is limited only by the appended claims.

I claim:

1. A planishing machine for correcting contour inaccuracies in the shape of a welded workpiece without damaging the weld connections, comprising,
a frame,
an axle rotatably mounted on said frame,
an anvil roll fixed on said axle having a peripheral surface complimentary to the desired shape of the workpiece;
said anvil roll having means for receiving, positioning, and holding a workpiece thereon,
first and second pairs of trunion sockets mounted on said frame triangulating with said anvil roll axle and with each other,
first and second power cylinders having trunnions mounted in said first and second pairs of trunion sockets,
a ram extending from each said cylinder toward said anvil roll,
pivot pins mounted on said frame outwardly of said anvil roll and outwardly relative to each said ram; a pair of swing arms having triangulated action points positioned between each said ram and said anvil roll and pivotally swingable at one action point on said pivot pins;
a cross-bar on each said pair of swing arms at a second action point having a connecting rod connected to one said ram,
a shaft between each said pair of swing arms at a third action point, a form roll on each said shaft for bearing against said anvil roll;

each said ram, connecting rod, cross-bar, and form roll lying substantially on an axis with said pivot pin off-set relative thereto;

said power cylinders, when retracting said rams, connecting rods, and cross-bars, swinging said arms on said pins to move said form rolls away from said anvil roll;

said power cylinders, when advancing said rams, connecting rods, and cross-bars, swinging said arms on said pins to move said form rolls toward said anvil roll and into forced engagement with the workpiece, and

means rotationally driving said anvil roll and said form rolls at substantially the same peripheral surface speed to pass the workpiece between said rolls in forced engagement to planish the workpiece to the desired shape.

2. In a machine as set forth in claim 1, said anvil roll having a relieved portion in the location of the welds of the workpiece to diminish the strain imposed on the welds.

3. In a machine as set forth in claim 1, said means rotationally driving said anvil roll comprising a worm gear on said axle, a worm driving said worm gear, and power means for driving said worm.

4. In a machine as set forth in claim 1, said means rotationally driving said form rolls comprising,

a sprocket gear keyed to each said form roll, a sprocket gear free on said pin, a spur gear free on said pin, a stud connecting said sprocket gear on said pin with said spur gear on said pin, and a final drive chain transferring drive between said sprocket gear on said pin and said sprocket gear keyed to said form roll,

a stub shaft rotatably bearinged on said frame,

a pinion gear keyed on said stub shaft engaging said spur gear, and a second sprocket gear keyed on said stub shaft, an idler sprocket ear on one said paired arms, a fluid motor on said frame having a drive shaft, a prime drive sprocket gear on said gear motor drive shaft, and

a prime drive chain leading over said prime drive sprocket gear, over said second sprocket gears on said stub shafts, and under said idler sprocket gear.

5. In a machine as set forth in claim 1, the workpiece being a brake-shoe having an arcuate plate and an arcuate web, said anvil roll relieved portion being a radial slot for receiving the web of a brake shoe, and said anvil roll having a surface complimentary to the desired shape of the arcuate plate.

10 6. In a machine as set forth in claim 1, said means for rotationally driving said anvil roll comprising,

an axle in said anvil roll; a key lying between said axle and said anvil roll preventing relative angular motion to provide rotational drive to said anvil roll and permitting relative axial movement to provide for withdrawing said axle from said anvil roll; said axle having opposite end,

15 a first sleeve housing said axle at one end thereof, on one side of said anvil roll,

a second sleeve housing said axle at the other end thereof on the other side of said anvil roll,

bearings rotatably mounting said sleeves,

a worm gear mounted on one said sleeve to import rotational drive to said sleeve,

said sleeve carrying said worm wheel being keyed to said axle to import rotational drive to said axle;

said key connection between said sleeve and said axle allowing relative axial movement of said axle;

20 a power cylinder mounted on said frame, on the axis of said axle, and a piston rod leading from said cylinder and connecting to said axle axially thereof;

said power cylinder and piston rod being capable of withdrawing said axle from said anvil roll when mounted to dismount said anvil roll and of advancing said axle through said anvil roll when dismounted to mount said anvil roll.

* * * * *
